Patented Dec. 4, 1917.

Ernest P. Vincent,
Inventor
By his Attorney

Thomas A. Hill.

UNITED STATES PATENT OFFICE.

ERNEST P. VINCENT, OF NEW YORK, N. Y.

CLOTHES-HANGER.

1,248,577.

Specification of Letters Patent. Patented Dec. 4, 1917.

Application filed February 4, 1916. Serial No. 76,082.

To all whom it may concern:

Be it known that I, ERNEST P. VINCENT, a subject of the King of Denmark, residing at the borough of Manhattan, in the county of New York and State of New York, have invented certain new and useful Improvements in Clothes-Hangers, of which the following is a specification, reference being had therein to the accompanying drawing.

My invention relates to improvements in clothes hangers, and more particularly has reference to a collapsible or folding hanger adapted to advantage for use when traveling.

In the accompanying drawings I have illustrated in Figure 1 a perspective view of an embodiment of my invention. Fig. 2 is a view of the hanger shown in Fig. 1 when closed or folded conveniently to be placed in a grip or traveling bag. Fig. 3 is a similar view to Fig. 1 embodying modifications, and Fig. 4 shows the hanger in Fig. 3 when closed or folded. Fig. 5 is a cross section of a modified form of channel or bar which may be used. Fig. 6 illustrates another modification of bar. Fig. 7 is a detail, partly broken away, illustrating the application of suitable hangers or hooks which may be combined with the lower bar of the clothes hanger as illustrated in Figs. 1 and 3. Fig. 8 is a cross section on the line 8-8 of Fig. 3 illustrating a modified form of locking means, and Fig. 9 is a cross section on the line 9-9 of Fig. 1 illustrating another form of locking means.

In the form of my invention illustrated in Fig. 1 the channels 10-11 are preferably pivoted at 12 and the channel 10 is preferably cut away as indicated at 13. Upon the pivot 12 is preferably mounted a suitable hook such as 14, the upper end 15 of which is preferably pivoted at 16 as shown so as to enable the same to be closed in thus reducing the diameter of the hook and enabling the same to be compactly folded with the body of the hanger when not in use as shown in Fig. 2. 17-18 are channels pivoted at their outer ends to the channels 10-11 as shown and at their inner ends at 19. The ends of said channels preferably overlap as shown to better advantage in Fig. 9 so that when in alinement as shown in Fig. 1 the depressions such as 20-20' interlock; thus serving to maintain rigidly in alinement the channels 17-18, and the chan-

nel 17 is also preferably cut away at 21 so as to enable the shank 14 of the hook to pass therethrough when folded. 22-23 are suitable hooks which may be suitably fastened within the channel by any suitable means 60 such as the clip 24 shown to better advantage in Fig. 7. In order to fold or collapse the hanger it is only necessary to press slightly upwardly at the junction of the bars 17-18 allowing the same to pass within 65 the channels 10-11 and bringing the opening 21 in line with the opening 13, after which the hook 14-15 may be collapsed; thus reducing its diameter and allowing it also to be pressed downwardly through the 70 openings 13-21. When it is desired to use the hanger the finger nail may readily be introduced beneath the end 15 of the hook and the lower bar 17-18 may readily be pulled out of the channels 10-11; thus immediately placing the hanger in condition 75 for use. The bars 10-11 serve conveniently for the coat and the bars 17-18 for the trousers, while at the same time the hooks 22-23 may be used to suspend a skirt or 80 any other garment.

In the modification shown in Fig. 3 it will be observed that the invention is susceptible of application by the use of wire in which case the coat hanger bars would preferably be bent substantially in U-shape as indicated by the reference characters 25-26, the upper ends being turned over hook fashion to receive the pin 12' upon which the hook of the hanger may be pivotally mounted in the usual manner. The lower end of the U-shaped bars also serve as a bearing for the channels 17-18 and on reference to Fig. 8 a modified form of locking device is observed to advantage. This comprises a 90 catch such as 27 which may be riveted or secured in any suitable manner upon the outer bar 18 as indicated at 28, the offset of the catch 27 serving to engage the edge of the inner bar 17 as shown. The appearance of 100 the wire hanger illustrated in Fig. 2 when collapsed is shown to better advantage in Fig. 4. The cross section of channel shown in Fig. 5 may be found a preferable form owing to the rounded shoulders such as 29 105 which will probably have less wear upon the clothing, or the deeper form of channel shown in Fig. 6 may be employed and a top surface of wood or other suitable material suitably rounded may be suitably secured 110

thereto, the same being indicated by the reference character 30.

Of course it will be understood that various modifications may be made in the construction and details of my invention without departing from the spirit of the same as claimed.

I claim:

1. In an article of the class described, 10 shoulder members hinged together whereby the same may be folded one substantially entirely within the other, and cross members adapted to be closed within said shoulder members when said article is folded.
- 15 2. A garment hanger comprising channel shoulder members hinged together, a two-piece channel cross member pivoted at the center and at the ends of said shoulder channels, said hanger being adapted to be

folded substantially within one of said 20 shoulder channels.

3. A garment hanger comprising channel shoulder members hinged together, said members substantially straight and adapted to be folded parallel, a two-piece channel 25 cross member pivoted at the center, and at the ends to said shoulder channels, a hook for said hanger and said hanger members cut away to clear said hook whereby said hook may be folded between said members 30 when said hanger is folded.

In testimony whereof I hereunto affix my signature in the presence of two witnesses.

ERNEST P. VINCENT.

Witnesses:

LOUISE ENDERLE,
THOMAS A. HILL.
